UNITED STATES PATENT OFFICE.

JOHN H. KENNEDY, OF DIXON, ILLINOIS.

OVEN ATTACHMENT FOR FURNACES.

1,159,684.

Specification of Letters Patent.

Patented Nov. 9, 1915.

Application filed April 16, 1915. Serial No. 21,679.

To all whom it may concern:

Be it known that I, JOHN H. KENNEDY, a citizen of the United States, residing at Dixon, in the county of Lee and State of Illinois, have invented certain new and useful Improvements in Oven Attachments for Furnaces, of which the following is a specification.

The appliance which is the subject matter 10 of the present application for patent is designed for the purpose of converting the fuel-feed opening of a furnace into an oven for baking and cooking purposes.

The invention has for its object to provide 15 an attachment of the kind stated which is very simple in construction, and which can be readily applied or removed.

The object stated is attained by means of a novel combination and arrangement of parts 20 to be hereinafter described and claimed, reference being had to the accompanying drawing in which—

Figure 1 is a sectional view of a fragment of a furnace showing the attachment in 25 place, the latter being also in section; Fig. 2 is a plan view of the attachment; Fig. 3 is a front elevation thereof, and Fig. 4 is a longitudinal section of the attachment provided with a protecting partition.

Referring specifically to the drawing, 5 denotes the front of an ordinary furnace, provided with a fuel-feed opening 6 having a door 7 as usual. The oven attachment comprises a bottom plate 8 and a rear wall 9 30 rising therefrom and extending throughout the entire width thereof. The attachment also has narrow side walls 10 rising from the bottom plate at the inner end thereof and joined to the rear wall.

On the inner faces of the side walls 10 are 40 vertical guide grooves 11 designed to hold a rectangular open frame 12 carrying shelves 13, the ends of said frame seating in the grooves. The frame is removable, it being 45 slidably mounted in the grooves. The shelves are for the purpose of supporting potatoes or other food articles to be baked. If the fire is very hot, the shelf can be removed and a solid sheet 14 will be mounted in the 50 grooves 11, and as the latter are spaced from the rear wall 9, an air space is had between said wall and the sheet 14, the latter form-

ing a partition which extends entirely across the interior of the oven between the side walls 10, and from the bottom to the top. 55

In order to facilitate the mounting of the appliance, and the removal thereof, the front portion of the bottom plate 8 has recesses 15 to take lifters 16 similar to ordinary stove-lid lifters. 60

The appliance is so dimensioned that it fits snugly in the opening 6, the top wall of the latter forming the top of the oven, and the side walls of said opening, with the walls 10, forming the sides of the oven. The 65 attachment will be inserted far enough so that it may be closed by the door 7.

The attachment can be cheaply made of sheet iron, and it can be easily applied or removed, no alteration in the structure of 70 the furnace being necessary. The wall line which is next to the fire may have a facing of asbestos.

I claim:

1. An oven attachment for the fuel-feed 75 opening of furnaces, said attachment comprising a bottom plate, a rear wall and side walls rising from the bottom plate, the side walls being connected to the rear wall, and the inner faces of the side walls having vertical guide grooves which are spaced from the rear wall, and a shelf supporting frame removably mounted in said guide grooves. 80

2. An oven attachment for the fuel-feed 85 opening of furnaces, said attachment comprising a bottom plate, a rear wall and side walls rising from the bottom plate, the side walls being connected to the rear wall, the inner faces of the side walls having vertical guide grooves which are spaced from the 90 rear wall, and a partition removably mounted in said guide grooves.

3. An oven attachment for the fuel-feed 95 opening of furnaces, said attachment comprising a bottom plate, a rear wall and side walls rising from the bottom plate, the side walls being connected to the rear wall, said side walls being relatively narrow and forming, with the side walls of the fuel-feed opening, the side walls of the oven, the top 100 wall of the fuel-feed opening forming the top of the oven.

In testimony whereof I affix my signature.
JOHN H. KENNEDY.
